UNITED STATES PATENT OFFICE.

JAMES GRAHAM TURNBULL, OF MANCHESTER, ENGLAND.

COLLAR-SUPPORTER.

1,112,102.

Specification of Letters Patent. Patented Sept. 29, 1914.

Application filed April 10, 1913. Serial No. 760,132.

To all whom it may concern:

Be it known that I, JAMES GRAHAM TURNBULL, a subject of the King of Great Britain and Ireland, and resident of Longsight, 5 Manchester, England, have invented certain new and useful Improvements in Collar-Supporters, of which the following is a specification.

The invention relates to certain improvements in supports or stiffeners for holding 10 soft materials such as collars, cuffs and the like in a neat and extended position.

The invention comprises the use, in combination, in a support or stiffener as afore- 15 said, of a spring wire bent to a sinuous form with the sinuosities of regular and even formation and lying in a plane width-wise of the support as hereinafter described, pin-like piercing means and a sheath at each end 20 of the spring portion and each of said piercing means having a hump or kink adapted, on the sheath and piercing means becoming engaged, to temporarily lock such parts to each other.

25 The object of the present invention is to provide the spring wire central portion of a collar support or the like with pin-like pointed ends, each end having a hump or kink for locking it in a sheath.

30 A further object is to produce a support of this type in a simpler and cheaper manner than heretofore.

On the accompanying sheet of drawing, Figure 1 illustrates a face view (partly in 35 section) of the improved support constructed according to the invention, and Figs. 2 and 3 illustrate an elevational view and a sectional view of the sheath, respectively, all drawn to a magnified scale.

40 Referring to Fig. 1, *a* is the spring wire which is bent or folded to a sinuous form

of regular and even formation, with all the sinuosities lying in a plane width-wise of the support; *a'*, *a'* are the pin-like pointed ends of the wire which form the piercing 45 means, and *a²*, *a²* are the humps or kinks which, when the parts *a'* are inserted in the part *b'* of the sheath, are sprung into the holes *b²* to temporarily lock the sheath on to the spring wire and so retain the wire in 50 position when the support is in use. The outer shell portion of the sheath *b* is, preferably, of spherical formation but may be of any other suitable shape and may be plain 55 or ornamental.

In using the improved support it is first laid flat against the collar or other article to be supported and the pointed ends of the wire *a* are passed through the material of the collar, when the sheaths are applied. 60

What I claim is:

In a collar or like support or stiffener, the combination of a length of spring wire bent to a sinuous form, the sinuosities being of regular and even formation and lying in a 65 plane common to all and width-wise of the support, said wire having its ends pointed and near each of such pointed ends having a kink, and a sheath comprising an outer shell part and an inner tubular part, the 70 latter being closed at one end and open at the other end, and having a hole at one side to receive the kink in the pointed end of the wire, when the latter is inserted in the 75 sheath, as set forth.

In witness whereof I have hereunto set my hand in the presence of two witnesses.

JAMES GRAHAM TURNBULL.

Witnesses:

JOHN CAMP,
HENRY JUNEA.
